UNITED STATES PATENT OFFICE

116,533

DESIGN FOR A TEXTILE FABRIC

Curt Erwin Forstmann, Montclair, N. J.

Application April 28, 1938, Serial No. 76,838

Term of patent 3½ years

To all whom it may concern:

Be it known that I, Curt Erwin Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure of which is a plan view of a piece of the textile fabric embody-

ing the design of the present invention, the cloth depicted is of a single color.

The design comprises double stripes spaced at regular intervals, separated by roughened raised areas comprising three stitches giving the area between the double stripes the appearance of applied braid.

I claim:

The ornamental design for a textile fabric, as shown and described.

CURT E. FORSTMANN.
